UNITED STATES PATENT OFFICE.

HIRAM D. IRWIN, OF BECKLEY, WEST VIRGINIA.

REFRIGERATING CABINET.

Application filed June 12, 1925. Serial No. 36,719

To all whom it may concern:

Be it known that I, HIRAM D. IRWIN, a citizen of the United States, residing at Beckley, in the county of Raleigh and State 5 of West Virginia, have invented certain new and useful Improvements in Refrigerating Cabinets, of which the following is a specification.

This invention relates to refrigerating 10 apparatus and more particularly to a refrigerating cabinet for use in displaying and dispensing groceries such, for example, as vegetables, although other commodities may be displayed in and dispensed from the 15 apparatus. It is a well known fact that there is great waste in marketing vegetables such as lettuce, celery, radishes, tomatoes, etc., because such vegetables are liable to wilt and become unsalable if they are 20 merely arranged in trays or bins open to the atmosphere, as is ordinarily the case. Furthermore, unless such vegetables present a fresh appearance, they do not appeal to customers and sales are frequently lost on this 25 account. Therefore, the invention has as one of its objects to provide a refrigerating cabinet in which groceries such as vegetables may be displayed to best advantage and maintained in a perfectly fresh condition 30 at minimum cost for the ice employed in maintaining a refrigerating temperature within the cabinet.

Another object of the invention is to provide a refrigerating cabinet so constructed 35 that by the use of a minimum quantity of ice, a suitably low temperature may be maintained in the cabinet to refrigerate the vegetables or other commodities contained therein, the arrangement being such that the ice 40 employed is introduced into the cabinet at one point only, thereby obviating the necessity of packing ice about all sides of the several compartments.

Another object of the invention is to so 45 construct and arrange the cabinet and the ice chamber thereof, that when the cabinet is in use, full benefit will be derived from the ice and a complete exchange of heat units will take place and economy will thus 50 be effected.

Another object of the invention is to provide a refrigerating cabinet of such construction that the vegetables or other groceries displayed therein will be protected 55 from contamination and in every way maintained in a sanitary condition.

Another object of the invention is to so construct the cabinet that the compartments in which the vegetables or other commodities are stored and displayed may be readily removed when it becomes necessary to clean the circulating system of the cabinet, the removal of said compartments serving to expose all surfaces on which scum might 60 accumulate. 65

In the accompanying drawings:

Figure 1 is a perspective view of the cabinet embodying the invention.

Figure 2 is a vertical longitudinal sectional view through the cabinet. 70

Figure 3 is a transverse sectional view taken substantially on the line 3-3 of Figure 2, on an enlarged scale, looking in the direction indicated by the arrows. 75

Figure 4 is a sectional view on the line 4-4 of Figure 2, on an enlarged scale, looking in the direction indicated by the arrows. 80

Figure 5 is a detail sectional view illustrating the manner of securing the vegetable compartments within the body of the cabinet. 85

The cabinet proper comprises a body indicated in general by the numeral 1, which is preferably of oblong rectangular form and relatively narrow, and the said cabinet comprises side walls 2, end walls 3, and a bottom 4, each of the said walls and the said bottom comprising inner and outer sections within which is arranged a packing 5 of sawdust or other insulating material. An oblong rectangular frame 6 including sides 7, ends 8, and cross pieces 9, is disposed upon the top of the body of the cabinet with its side members 7 and its end members 8 resting upon and secured respectively to the upper sides of the side walls 2 and end walls 3 of the body of the cabinet. The cross pieces 9 of the frame serve to divide the frame into a number of rectangular sections in each of which there is hingedly mounted, at one side, a door 10 having a glass pane 11 arranged in its frame so as to expose to view the commodities which are arranged within the several compartments of the cabinet, as will be presently explained, a handle 12 being provided at that side of each door opposite its hinged side, so that the doors may be independently 90 swung upwardly to open position to permit of access being had to the corresponding compartments. 95

Normally, however, the 100

105

110

doors will remain closed with their relatively adjacent edges meeting each other and resting upon the cross pieces 9 so that the vegetables or the like which are stored 5 within the several compartments, will be protected from contamination, and, likewise, there will be no escape of cold air from the cabinet, the glass panes 11 providing for advantageous display of the 10 contents of the cabinet and, in fact, displaying the contents to a better advantage than if the commodities were placed in an ordinary open bin or tray.

Lining sheets 13 of sheet metal are secured to and extend over the inner faces of the side walls 2 of the cabinet, and these lining sheets extend for the entire length of the said side walls and from the upper side of the bottom 4 to a point slightly 15 spaced below the upper edges of the side walls. Similar lining sheets 14 are secured to the inner faces of the end walls of the cabinet, and a bottom lining sheet 15 is secured to and extends over the upper side 20 of the said bottom 4 of the cabinet, the edges of all of the sheets being united so as to provide fluid-tight joints and thus prevent seepage of water to the walls and bottom of the body of the cabinet.

It will be observed at this point that the cabinet is supported in an inclined position, rather than horizontally, one end of the cabinet resting upon one end of a base board 16, and the other end of the cabinet being 25 supported in an elevated position by an upright 17 mounted upon the other end of the base board. Side boards 18 are arranged to extend along the opposite longitudinal edges of the base board 16 and are likewise 30 secured to the bottom of the cabinet at opposite sides of the lower end thereof, and partitions 19 extend upwardly from the base board 16 and the side boards 18 and serve to divide the base structure into bins 20 35 in which groceries such as potatoes, onions, and the like, which do not require refrigeration, may be stored. The purpose in mounting the cabinet in inclined position will presently be more fully explained.

The cabinet includes a multiple compartment storage unit which is indicated in general by the numeral 21, and this unit is preferably made, in its entirety, from sheet metal. The unit comprises side walls 22 40 which are provided at their upper edges with longitudinally extending flanges 23 which project outwardly at right angles and extend above the flanges 24 which are formed along the upper edges of the lining sheets 13, packing strips 25 being interposed between the flanges, and screws 26 being fitted through openings in the flanges 23 and threaded into openings formed in the flanges 24. At intervals in its length, 45 each of the side walls 22 is formed with a port or sustain the bottoms of the compartment 27 extending nearly to the upper edge of the wall and opening at its lower end through the lower edge of the wall. The bottom of the unit, indicated in general by the numeral 28, is 50 preferably formed from a single long sheet of metal which at intervals in its length is bent to provide spaced wall portions 29 which are substantially perpendicular to the said bottom 28 and are united at their upper ends by integral portions 30 of the same plate. The portions of the plate which constitute the bottoms of the several compartments, which compartments are indicated in general by the numeral 31, are indicated by 55 the numeral 32, and the side edges of these portions and likewise the side edges of the portions 29, are formed with flanges indicated respectively by the numerals 33 and 34, these flanges being welded, soldered, or otherwise secured in a fluid-tight manner to the inner faces of the side walls 22, the flanges 33 being secured to the said side walls along the lower edge portions of the latter and between the slot 27, and the flanges 34 being secured to the said side walls 22 at the opposite side of the slot 27. In this manner, the unit is formed to provide the compartments 31 referred to, in which compartments the vegetables or the like to be displayed and dispensed, are stored, and it will be evident that the portions 29 and 30 constitute hollow partition walls dividing relatively adjacent ones of the compartments, the partition walls being closed at their tops and open at their bottoms. One of the partition walls, indicated specifically by the numeral 36, constitutes the end wall of the unit as a whole and constitutes a portion of the plate from 60 which the bottom is formed, bent upwardly at right angles to the respective bottom portion 32 and located relatively close to the lower end wall of the body of the cabinet. A partition wall 35 is fixed within the body 65 of the cabinet and is spaced somewhat from the upper end wall of the cabinet so as to provide an ice compartment indicated by the numeral 37.

In order that the sides of the multiple compartment unit may be maintained spaced with relation to the lining sheets 13 or, in other words, the side walls of the cabinet, spacing members 38 are provided and each of these members comprises a length of V-angle iron 39 having flanges 40 extending along its longitudinal edges and secured in any suitable manner to the inner sides of the sheets 13, the ridges of the angle iron pieces being engaged by the outer sides 45 of the side walls 22 of the said multiple compartment unit. The compartments 31 are of less depth than the interior of the cabinet body, and in order to suitably support the bottoms of the compartments 31, 50 each of the side walls 22 is formed with a port or sustain the bottoms of the compartments 31.

ments, short angle iron pieces 41 of the same form as the pieces 39 are secured, preferably in pairs, as in the case of the members 38, upon the upper side of the bottom sheet 13 of the cabinet body beneath each of the compartments 31.

The numeral 42 indicates an overflow pipe which has its upper end fitted through the lower end wall of the cabinet near the top thereof, and the said pipe extends beside the said end wall of the cabinet and preferably through an opening 43 in the floor F upon which the structure is disposed. An elbow section 44 is preferably fitted to the lower 15 end of the pipe 42, or the lower end of the pipe may itself be bent upwardly to substantially U-form, so as to provide a water seal to prevent the entrance of insects into the cabinet by way of the pipe. A faucet section 45 is fitted in the partition wall 35 near the bottom thereof, and the valve of the faucet is provided with a relatively long stem 46 which extends upwardly between said wall and the adjacent side of the uppermost one 20 of the storage compartments 21 and is provided with a handle 47 at its upper end whereby the valve may be readily opened and closed.

The invention contemplates filling the ice compartment 37 with ice, and pouring in through this compartment a quantity of water which will be cooled by the ice and will cool the walls of the several compartments 31, and in order to maintain a proper water lever about the compartments and avoid flooding of the cabinet, means is provided which will now be described. The means referred to comprises a series of damming baffles indicated in general by the numeral 45 and positioned each within the bounds of a respective one of the hollow partition walls 29. Each of the damming baffles is preferably formed from a sheet of metal folded upon itself as at 46 to provide 30 slightly diverging walls 47 which, at their lower edges, are provided with outstanding flanges 48 secured in any suitable fluid-tight manner to the upper side of the bottom sheet 15 of the cabinet, the said walls 47 at their lateral edges being provided with similar flanges 49 which are secured in a fluid-tight manner to the inner faces of the lining sheets 13. The baffles are so spaced throughout the series that they will be symmetrically spaced with relation to the sides and tops of the respective partition walls 29 within which they are received, and by reference to the drawings and particularly Figure 2 thereof, it will be observed that the damming baffles project upwardly into the respective partition walls nearly to the top thereof except in the case of one or more of the baffles which are located near the upper end of the cabinet and which baffles are successively decreased in height in order 40 ranging in the direction of said upper end of the cabinet.

It will now be evident that the damming baffles, in effect, divide the interior of the body of the cabinet into a number of water compartments, and that the compartments 31 of the multiple compartment unit are substantially immersed in the water present in the respective water compartments of the cabinet body. The process of refrigeration 75 is begun by packing a quantity of cracked ice in the ice compartment 37 and then opening the faucet 45' and pouring sufficient water into this compartment to bring the water level in the several water compartments of the cabinet body to a point where water will overflow through the pipe 42. As some of the ice will be melted when the water is first introduced, additional ice is then introduced into the compartment 37 until the 80 compartment is filled. As the ice melts, water will flow over the upper edge of the uppermost damming baffle into the first water compartment of the cabinet body, and water will be displaced from this compartment and overflow over the upper edge of the next damming baffle, and so on throughout the series, so that there is a continuous discharge of water from the lower end of the overflow pipe 42. The 85 ice water in the water compartments of the cabinet body will, of course, surround all sides and the bottoms of the respective compartments 31 so that the vegetables or other groceries contained in the compartments 31 will be kept at a sufficiently low 90 temperature to keep them in a fresh condition for several days. By forming the baffle which is nearest the upper end of the cabinet, of less height than the other baffles, 95 water at a very low temperature will be delivered more quickly to the water compartments near the bottom of the cabinet, inasmuch as the upper water compartment will 100 fill and overflow more quickly than the said lower compartments. Furthermore, inasmuch as the upper water compartment is nearer the ice compartment 37, it requires a less volume of water to cool the respective compartment 31 than is required in the case 105 of the lower compartments.

If desired, an oblong rectangular frame 50 of narrow beading may be provided and removably disposed within the top of the cabinet to rest upon the flanges 23 and thus 110 hide the heads of the screws 26, it being understood that this frame may be readily removed and the screws 26 removed so as to permit of bodily removal of the multiple compartment storage unit when it becomes 115 necessary to clean the scum from the walls and bottom of the water compartment within the cabinet and from the baffles 45.

The lower end of the multiple compartment storage unit is preferably spaced from 120

4
the lower end wall of the cabinet body by a spacing member 51 of the same general form as the members 38 and 41.

Having thus described the invention, what

5 I claim is:

1. A refrigerating cabinet comprising an inclined cabinet body having an overflow at its lower end, and an ice compartment at its upper end, a plurality of storage compartments within the body, and damming baffles within the body arranged between successive ones of the storage compartments to dam the overflow from the ice compartment and maintain a body of cold water about the walls of the storage compartments.

15 2. A refrigerating cabinet comprising a cabinet body having an inclined bottom, the body having an overflow at its lower end; and an ice compartment at its upper end, a plurality of storage compartments within the body spaced from the walls thereof and from the bottom of the body, and damming baffles within the body extending upwardly from the bottom thereof between the said storage compartments and transversely between the side walls of the body whereby to provide a plurality of cold water compartments, each accommodating a respective one of the storage compartments and whereby to dam the overflow from the ice compartment and maintain a body of cold water in each water compartment.

25 3. A refrigerating cabinet comprising an inclined cabinet body having an overflow at its lower end located near its top, an ice compartment at the upper end of the body in communication at its bottom with the interior of the body, an inclined series of storage compartments within the body spaced from the walls of the body and from the bottom of the body, and a plurality of damming baffles upstanding from the bottom of the body and extending between the side walls thereof and located between the said storage compartments whereby to dam the overflow from the ice compartment and maintain a constant level of water in the spaces between the said baffles and about the walls of each storage compartment.

40 4. A refrigerating cabinet comprising an inclined cabinet body having an overflow at its lower end and an ice compartment at its upper end, a multiple compartment storage unit comprising a series of compartments and intervening hollow partition walls dividing the same, the partition walls being closed at their tops and open at their opposite sides and bottoms, and damming baffles within the partition walls upstanding

45 from the bottom of the cabinet body and constituting means for damming the overflow from the ice compartment and thereby maintaining a body of cold water about the walls of each storage compartment.

5. A refrigerating cabinet comprising an inclined cabinet body having an overflow at its lower end and an ice compartment at its upper end, a multiple compartment storage unit comprising a series of compartments and intervening hollow partition walls dividing the same, the partition walls being closed at their tops and open at their opposite sides and bottoms, damming baffles within the partition walls upstanding from the bottom of the cabinet body and constituting means for damming the overflow from the ice compartment and thereby maintaining a body of cold water about the walls of each storage compartment, the said multiple compartment storage unit being bodily removable, and means upon the walls and bottom of the cabinet body for spacing the corresponding walls and the bottom of the said unit therefrom and thus provide a water space about all sides of each compartment of the unit.

6. A refrigerating cabinet comprising an inclined cabinet body having an overflow at its lower end, and an ice compartment at its upper end, a plurality of storage compartments within the body, damming baffles within the body arranged to dam the overflow from the ice compartment and maintain a body of cold water about the walls of each storage compartment, a frame extending over the top of the said cabinet body and having openings therein above the storage compartments, and a hinged door for closing each of said openings individually.

7. A refrigerating cabinet comprising a body, an inclined series of storage compartments within the body, an overflow pipe leading from the body at that end thereof next adjacent the lower end of the series, an ice compartment within the body at the upper end of the series, and baffles within the body between said compartments for maintaining successively elevated bodies of water about each of said storage compartments, from the overflow end of the body to the end at which the ice compartment is located, the uppermost baffle being of less height than the other baffles, whereby the cold-water level about the upper baffles will be lower than that about the lower baffles.

110
115
In testimony whereof I affix my signature.

HIRAM D. IRWIN. [L.S.]
